UNITED STATES PATENT OFFICE.

LEWIS T. CANFIELD, OF CHICAGO, ILLINOIS, ASSIGNOR TO UNION DRAFT GEAR COMPANY, OF CHICAGO, ILLINOIS, A CORPORATION OF DELAWARE.

RAILWAY CAR.

Application filed August 3, 1925. Serial No. 47,686.

The invention relates to means for applying draft and buffering devices to railway cars, its objects being to provide a removable buffer plate; to provide a construction in which the draft gear may be inserted longitudinally between the draft sills and be supported directly by such sills; and to provide further improvements in the application of draft devices to railway cars, that will hereinafter appear.

The invention consists in a structure such as illustrated in the accompanying drawing, in which

Fig. 1 is a detail vertical central longitudinal section through a car frame, with the improved device applied;

Fig. 2 is a similar view with the movable parts in different position;

Fig. 3 is a detail plan section through the car framing and the draft device;

Fig. 4 is a detail plan view of the central portion of a car framing, with a modified form of the improved device applied thereto, a portion of the end wall of the car being shown in section;

Fig. 5 is a detail sectional view on the line 5—5 of Fig. 4;

Fig. 6 is a detail transverse vertical section on the line 6—6 of Fig. 5;

Fig. 7 is a detail end elevation of the car;

Fig. 8 is a view similar to Fig. 1, the improved device being of somewhat modified form;

Fig. 9 is a sectional detail on the line 9—9 of Fig. 8;

Fig. 10 is a detail side elevation of one of the draft sills of the car, adapted for the application of the improved device of the form shown in Figs. 8 and 9;

Fig. 11 is a view in perspective of one form of retaining key used in the improved device;

Fig. 12 is a view similar to Fig. 8 showing a further modification;

Fig. 13 is a detail section on the line 13—13 of Fig. 12;

Fig. 14 is a view in perspective of a key-holding socket plate used in the form of the device illustrated in Figs. 12 and 13;

Fig. 15 is a detail plan view of a car framing and draft gear, some of the parts being shown in section; and

Fig. 16 is a detail sectional view on the line 16—16 of Fig. 15.

It has heretofore been the practice, and

so far as I am now advised, the invariable practice, to permanently secure the buffering block or plate with which the coupler horn makes contact under severe buffering actions permanently to the car frame while the car is undergoing the process of building. As a necessary result of this practice the draft gear must be applied by raising it up under the car frame and entering it between the draft sills from below. This involved the employment of such beam forms for the draft sills as would provide the necessary clearance to admit the draft gear, and it further compelled the use of a supporting saddle, usually in the form of a heavy bar attached to the sills for supporting the draft gear, the draft gear yoke riding upon this saddle and the draft gear proper being supported by the yoke.

The employment of a removable buffer block or plate as provided by this invention not only cheapens the original cost of manufacture of the car and permits the use of beams of stronger sectional form, but provides a better and more reliable support for the draft gear, improved means for transmitting the stresses of draft to the car frame, and facilitates the assembly of the parts and their removal for purposes of repair and replacement.

The buffering plate 20 is provided with an aperture through its face for the accommodation of the coupler butt 21, this aperture being surrounded by an instanding flange 22. Extending backwardly from the buffering plate 20 are a pair of side walls 23 adapted to fit between the center or draft sills 24, and when a sectional beam form for the draft sills is employed which provides an instanding foot flange, as shown for example in Fig. 6, the walls 23 may be flanged inwardly at their lower margins to conform to and rest upon such flanges.

The walls 23 are connected at their upper margins by a transverse wall 26, materially strengthening the structure. This top wall is provided with a shoulder 27 for bearing against the end sill 28 of the car. An outer vertical flange 29 may extend backwardly from each of the side margins of the plate 20, being spaced apart from the wall 23 to admit the web of the sill 24, this flange being turned outwardly as shown at 30 to engage the ends of the outstanding flanges of the sill.

The buffer element is retained in place by means of keys 31, 32 inserted through both its side walls 23 and the sills 24, and retained in place by any suitable means. The positioning as well as the form of these keys, and the length of the walls 23 will be determined by the character of the draft rigging to be employed on the car. In the construction illustrated in Fig. 9 both the upper and lower keys 31 and 32 are of sufficient length to pass through both of the sills. They are headed at one end and secured in place either by cotters or bolts passing through suitable apertures adjacent their opposite ends. In the construction shown in Fig. 6 the lower keys 33, shown in perspective in Fig. 11 are of special form, the body portion being short and extending inwardly through the sill and terminating at the inner face of the wall 23. From this body portion there depends an outstanding flange adapted to seat upon the outer foot flange of the sill, to which it may be bolted as shown.

In the construction illustrated in Figs. 12, 25 13 and 14 the lower key 32 is of the long form and extends through downstanding extensions 34 of the walls 23 and through the eyes of socket plates 35 riveted to the foot flanges of the sills.

30 The vertical alignment of the upper and lower keys may be varied and they may be positioned longitudinally of the sills to adapt them for use in connection with different forms of yokes, and somewhat vary their function. For example, in Fig. 12 a form of yoke is shown which requires the upper key to be located well forward to provide sufficient clearance for the upper portion of the yoke, while in Fig. 8 the lower key is nearer the end of the sills than the upper one, for a like reason. In Figs. 1, 2 and 3 the keys are shown, one directly above the other, and are located well back from the end of the sills, the side walls 23 of the buffer element being correspondingly prolonged.

50 This latter arrangement is intended for use in connection with the shorter forms of draft gear, such as the well known Cardwell gear, which is outlined in Figs. 15 and 16. When this form of construction is followed a filler block 36 is slidably fitted between the keys 31, 32 and is interposed between the end of the coupler butt 21 and the forward follower of the draft gear, and may be provided with 55 forwardly facing shoulders 37, 38 for normally engaging the keys 31, 32 and transmitting thereto the stresses of draft. Under buffering stresses the block 36 moves backwardly with the coupler butt, as indicated in Fig. 2, causing the compression of the gear.

60 Draft stresses are transmitted to the car sills through the keys 31 and 32, or 33, and these stresses may be applied either directly to the keys as shown in Figs. 1 and 2 or there 65 may be formed on the side walls 23 of the

buffing element draft lugs 39, 39 as plainly shown in Fig. 4. When this construction is used the forward follower of the draft gear engages these lugs and the pressure is delivered for the keys through the walls of the 70 buffer element. Where a filler block such as 36 is employed, the draft lugs may still be provided, the shoulders 37 being omitted and the gear follower directly engaging the lugs. 75

As plainly shown in Figs. 15 and 16 the draft sills 24, 24 are provided with instanding longitudinal ledges, here preferably taking the form of foot flanges, upon which the draft gear 40 rides. Preferably the 80 varying portions of the gear elements will conform to the upper surface of this ledge. As shown, the ledge 41, being a mere flange formed in the rolling of the sill, has an inclined upper face and the bottom of the gear casing is correspondingly inclined. In the practice heretofore prevailing the draft gear yoke 42 has slidingly rested upon a saddle bar secured to the two draft sills and has supported the gear. In the present construction the gear being supported directly by the sills, such saddle bar may be dispensed with and the top member of the yoke will rest directly upon it. 85

In assembling, the buffer element is not applied until the draft gear is in place. The gear may be thrust in longitudinally between the sills, carrying with it the yoke 42. The buffer element may now be inserted and its retaining keys fitted in place. The coupler 90 21 may now be thrust in and secured to the yoke in the usual manner as by a key 43.

While preferred forms of construction have been shown and described, the invention 105 is of sufficient scope to include any form which provides for the removable attachment of a buffering element.

I claim as my invention:

1. A buffering casting for railway cars, such casting being apertured to form a throat for a draw-bar and having backwardly extending apertured side plates adapted to fit against the draft sills of a car, such sills being provided with apertures registering with the side plate apertures, and keys adapted to pass through the apertures of the plates and the draft sills. 110

2. A buffering casting for railway cars, such casting being apertured to form a throat for a draw-bar and having backwardly extending apertured side plates adapted to fit against the draft sills of a car, draft lugs carried by such plates, and keys adapted to pass through the apertures of the plates and the draft sills, the latter being correspondingly apertured. 120

3. A buffering casting for railway cars, such casting being apertured to form a throat for a draw-bar and having backwardly extending apertured side plates adapted to fit 125

against the draft sills of a car, a top plate connecting the side plates, and keys adapted to pass through the apertures of the plates and the draft sills, the latter being correspondingly apertured.

4. A buffing casting for railway cars, such casting being apertured to form a throat for a draw-bar and having backwardly extending apertured side plates adapted to fit against the draft sills of a car, a shoulder for abutting against an end sill of the car, and keys adapted to pass through the apertures of the plates and the draft sills, the latter being correspondingly apertured.
- 10 5. A buffing casting for railway cars, such casting being apertured to form a throat for a drawbar and having backwardly extending apertured side plates adapted to fit against the draft sills of a car, keys adapted for detachably securing the side plates to such sills, and a filler block slidably mounted between the side plates and the keys for transmitting buffing stresses from a draw-bar to a draft gear.
- 15 6. A buffing casting for railway cars, such casting being apertured to form a throat for a draw-bar and having backwardly extending apertured side plates adapted to fit against the draft sills of a car, keys adapted for detachably securing the side plates to

such sills, and a filler block slidably mounted between the side plates and the keys for transmitting buffing stresses from a draw-bar to a draft gear, such block having shoulders for engaging the keys to 35 transmit draft stresses thereto.

7. In a railway car in combination, an end sill, a pair of center sills extending under the end sill, a buffing element bearing on the end sill and having extensions bearing on the sides thereof, the buffing element being secured in place by keys passing through the center sills and such extensions.

8. A buffing element for railway cars adapted to loosely bear against the end and center sills of a car and having rearward extensions for engaging the side faces of the center sills, such extensions being apertured for the reception of attaching keys.

9. In a railway car, in combination, a pair of draft sills each having an instanding horizontal ledge, a draft gear slidably supported on such ledges, a buffing block, and a pair of keys for removably securing the block to the sills and for transmitting 50 draft stresses to such sills.

In testimony whereof I affix my signature.

LEWIS T. CANFIELD.
